FIG. I.

13 —

Fig. 2.

Inventor

22 William T. Horne

By Fred Stodges

Attorney

UNITED STATES PATENT OFFICE

WILLIAM T. HORMES, OF CATONSVILLE, MARYLAND

CASTER

Application filed August 9, 1927. Serial No. 211,754.

This invention is a caster for supporting the slidable doors or panels of display racks, cabinets and the like.

Display racks and cabinets of the so-called "enclosed" type, for convenient display of ready made garments and other merchandise generally, are now in extensive use as standard equipment in mercantile establishments. They are usually constructed with glass walls or panels, so that the goods on display may be readily seen by prospective customers, the front wall of a case or compartment being usually made up of slidable doors or sections, which may be moved to permit ready access to the articles within the case. In order that the articles on display may be protected from dust and similar contamination it is desirable, and in fact important that a substantially close contact be maintained between the edges of the door and the surfaces with which they cooperate. One of the objects of the invention is to provide a caster designed to meet the above mentioned requirements. A further object is to provide a caster capable of being readily secured to the door or other article which it is intended to support, and to provide means for effecting vertical adjustment of the supporting roller with respect to the said article, so that the article may be properly positioned within the opening in which it is operating. A further object is to provide means for permitting a swivelling movement of the roller when the article is moved, without affecting the vertical adjustment. A further object is to provide a caster which may be made to travel within a track-way, and be capable of readily accommodating itself to any change of direction necessitated by a bend in the track.

The invention will be hereinafter fully set forth and particularly pointed out in the claims.

In the accompanying drawing:—

Figure 1 is a perspective view illustrating 45 a caster constructed in accordance with the in-

vention and applied to a sliding door. Figure 2 is a vertical sectional view of the caster. Figure 3 is a horizontal sectional view on the line 3—3, Figure 2. Figure 4 is a detail view illustrating the adjusting nut.

50

Referring to the drawing, 10 designates a portion of a sliding door or panel, such as the door of a display cabinet or the like, and 11 the track-way for the caster. Secured to one face of the door 10 is a casing 12, which is provided with perforated ears 13, to receive the securing screws 14, by which the casing is attached to the door 10. Said casing is provided with a rearwardly extended shelf portion 15 positioned to extend under the lower edge of the door so as to support the same.

55

The casing 12 is provided with a barrel-like portion 16, having its upper end closed by a top wall or abutment plate 17, its lower end being open. Said barrel portion is provided with a slot 18 contiguous to the top wall 17, as shown, and an opening 19 is formed in said top wall, said opening being of smaller diameter than the internal diameter of the barrel portion 16.

65

The caster member consists of a cylindrical body 20, provided with arms 21 carrying a pin or rod 22, on which is rotatably mounted the wheel 23, in a well known manner. Extending upwardly from the body 20 is a shank 24, and if desired, a fiber lubricating ring 23^a may be set into the top of the body 20 so as to encircle said shank. Loosely mounted upon the shank 24 so as to permit relative rotation is a sleeve 25 provided with external screw threads 26. Said sleeve is of less diameter than the caster body 20 so that its lower end terminates opposite the top face of said body. Said sleeve is of approximately the same length as the shank 24, and is held against endwise movement relative to the shank in any desired manner. For instance the free end of the shank may be pinched or spread over the adjacent end of the sleeve. Said sleeve is smaller in cross

70

75

80

85

86

section than the diameter of opening 19. A portion of the threaded surface of the sleeve 25 is cut away and flattened, as indicated at 27, and a stop pin 28 is driven through the top 5 wall 17 across a portion of the opening 19, so as to engage the cut away or flattened portion 27 of said sleeve, and prevent rotation of the sleeve with respect to the casing 12. Rotatably mounted upon the sleeve 25 is a nut 29, 10 which is of approximately the same diameter as the caster body, and interposed between said body and said abutment plate so that it may engage either of them. Said nut may be rotated in suitable manner, as by means of 15 a tool shaped to engage peripheral recesses 30. Said nut is provided with a tapered extension 31, complementary to a correspondingly shaped portion of the opening 19. By this arrangement, the sleeve 26 is held in concentric relation with the opening, and binding of 20 the parts prevented.

In practice, the caster member with the attached sleeve 25 and associated nut 29 is passed upwardly through the open bottom of 25 the barrel member 16, and extended through the opening 19, until the upward movement is prevented by reason of the nut 29 abutting against the underside of the wall or abutment plate 17. The sleeve 25 is then rotated so 30 as to bring the cut-away surface 27 parallel with the vertical wall of the casing 10, and the pin 28 is then driven through the shelf 17 in a chord-like position with respect to said opening. In this manner the rod 28 will engage 35 the flattened portion 27 of the sleeve 25 and prevent rotation thereof, and will also limit longitudinal movement of the sleeve and thereby prevent the caster from dropping out of the casing, because said rod will engage the 40 shoulder formed at the upper end of the flattened portion 27 and prevent the sleeve from passing out of the hole 19. The assembled caster and casing are secured to the door 10 in suitable manner, as by means of screws 14 passed through the ears 13.

After the casing has been attached to the door and the roller 22 placed in the track 11 in a well known manner. It will be noted that the nut 29 fills the space between surfaces of the abutment plate 18 and the caster body 21, and rotatably engages both of them. By this arrangement, play between the parts is reduced to a minimum and the nut cooperates with both surfaces to obtain a jacking effect in adjusting the caster either upwardly or downwardly. In practice, the nut 29 is adjusted to raise or lower the door as the case may be, and thereby bring the lower end of the door sufficiently close to the track 11 to reduce to a minimum the space through which dust and other contaminating material may pass into the cabinet to which the door is secured. It will be noted that the wall 17 acts as an abutment member for the nut 29 and 65 that the weight of the door is carried by the

shelf 15 and also the caster member through the interposed nut 29. The tapered extension 31 serves to maintain the nut 29 in a concentric position with respect to the sleeve 25.

The advantages of the invention will be 70 readily apparent to those skilled in the art to which it belongs. It will be particularly noted that a very simple form of adjustable caster is provided, which is capable of freely swivelling under the operation of the door, so 75 as to readily conform to the curvatures of the track without disturbing any adjustment which may have been made. It will be further observed that where a plurality of casters are employed to sustain a movable article, 80 they may be individually adjusted without difficulty so as to maintain the article in a perfectly level position. This is particularly important in the case of a door which may be mounted to freely slide without binding. 85

It is to be understood that although the invention has been described as particularly adapted for use on the doors of display cabinets and the like, this application of the invention has been selected solely for illustrative purposes. The invention, however, is not limited to this specific use, but may be employed for movably supporting articles of furniture, and any other articles of the type normally supported by casters. 95

Having thus explained the nature of the invention and described an operative manner of constructing and using the same, although without attempting to set forth all of the forms in which it may be made, or all of the forms of its use, what is claimed is:— 100

1. A caster of the character described comprising a caster member provided with a cylindrical body and a longitudinally extended shank, a supporting casing having a barrel with which the periphery of said caster body has rotative engagement, said casing also having an abutment plate spaced from one end of said barrel and provided with an opening through which said shank extends, said opening having a tapered portion, an exteriorly threaded sleeve rotatably engaging said shank and also extended through said opening but held against longitudinal movement with respect to the shank, a nut rotatably engaging said sleeve, said nut being interposed between and engaging oppositely disposed surfaces of said abutment plate and said caster body, said nut having a tapered sleeve complementary to the tapered portion of said opening, and means unaffected by adjustments of the caster for normally preventing rotation of said sleeve. 110

2. A caster of the character described comprising a caster member provided with a cylindrical body and a longitudinally extended shank, a supporting casing having a barrel with which the periphery of said caster body has rotative engagement, said casing also having an abutment plate spaced from one end 125

of said barrel and provided with an opening through which said shank extends, an exteriorly threaded sleeve rotatably engaging said shank and also extended through said opening, a nut rotatably engaging said sleeve, said nut being interposed between and engaging oppositely disposed surfaces of said abutment plate and said caster body, and a pin extended through the opening in said abutment plate and having a portion exposed within said opening, said sleeve having a longitudinal recess positioned to engage said pin so as to prevent rotation of the sleeve.

10 In testimony whereof I have hereunto set
15 my hand.

WILLIAM T. HORMES.
